CLAIM

The ornamental design for a gaming machine divider, as shown and described.

DESCRIPTION

FIG. 1 is a front perspective view of a gaming machine divider showing our new design according to a first embodiment;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a front perspective view thereof, showing the gaming machine divider positioned between two example gaming machines in dashed broken lines for environmental purposes; and,

FIG. 9 is another front elevation view thereof, showing our new design in an illuminated state.

The dashed broken lines in the drawings illustrate example environment and portions of the gaming machine divider that form no part of the claimed design.

The radiating lines in FIG. 9 represents the glowing visual effect created by light emanating from the gaming machine divider.
